Patented Oct. 13, 1914.

UNITED STATES PATENT OFFICE.

ROBERT HOPE-JONES, OF NORTH TONAWANDA, NEW YORK, ASSIGNOR TO THE
RUDOLPH WURLITZER MANUFACTURING COMPANY, OF NORTH TONAWANDA,
NEW YORK, A CORPORATION OF NEW YORK.

STOP-OPERATING DEVICE FOR MUSICAL INSTRUMENTS.

1,113,439.

Specification of Letters Patent.

Patented Oct. 13, 1914.

Application filed December 26, 1911. Serial No. 667,800.

To all whom it may concern:

Be it known that I, ROBERT HOPE-JONES, a subject of the King of England, residing at North Tonawanda, in the county of 5 Niagara and State of New York, have invented new and useful Improvements in Stop-Operating Devices for Musical Instruments, of which the following is a specification.

10 This invention relates to a device for operating or controlling the movable members of pneumatic musical instruments such, for example, as the slides or registers of pipe-stops. When such stops are used, for example, in an automatic piano additional tracker ducts are required for throwing them "on" and "off" and a correspondingly wider music sheet is necessary. It is well known that the degree of expansion or 20 contraction of such sheets under atmospheric changes increases with their width, and it is therefore desirable to make them as narrow as possible.

The object of my invention is the provision of a simple and reliable apparatus by 25 which a comparatively large number of such stops or additional sound producing devices can be automatically operated or controlled without correspondingly increasing the length of the tracker and the width 30 of the music sheet, thus enlarging the scope of the instrument without unduly widening the music sheet.

In the accompanying drawings: Figure 35 1 is a diagrammatic view of the apparatus, partly in section. Fig. 2 is a vertical section of the motor pneumatics of the stop-slides and the rotary controlling valve. Fig. 3 is a top plan view of the block or 40 case with which said valve co-operates. Fig. 4 is a bottom plan view of the rotary valve. Fig. 5 is a cross section of the slide-valve.

Similar letters of reference indicate corresponding parts throughout the several 45 views.

A indicates the tracker having the customary main ducts a which control the piano strings or other principal sound producing parts, and a^1 , a^2 indicate a pair of 50 supplemental ducts which control a plurality of stops B, B^1 , the duct a^1 serving to throw the stops "on" and the duct a^2 to throw them "off." The music sheet (not shown in the drawings) in addition to the

customary holes, has two rows of suitably 55 cut holes which coöperate with the ducts a^1 , a^2 .

Two stops, the xylophone and the violin, are shown in the drawings but a greater number may be employed, if desired, those 60 illustrated in the drawings being shown only by way of example.

b , b^1 indicate the usual slides of registers of the stops and C, C are motors or motor pneumatics which respectively actuate 65 said slides. The latter are suitably connected with the movable boards of these pneumatics, as shown in the drawings, and these boards are provided with springs c which tend to close the slides. In the example shown in the drawings the outer ends of these springs are attached to the fixed supports C^2 of the stops. Each of these stop controlling motors is connected by a tube or conduit d with one of a circular series of ports e formed in a block or case E, 70 preferably concentrically with a wind chamber E^1 which is alternately exhausted and flushed and with which one or more of the ports e are adapted to be connected so 75 as to collapse or expand the corresponding motors C, C and throw the stops into or out of action accordingly.

The connection of the chamber E^1 with any one of the ports e is effected by a switch 85 device preferably consisting of a rotary valve F mounted on a pin or screw f secured centrally in said chamber. In the construction shown, this valve is in the form of a ratchet disk provided on its underside with a radial port or groove f^1 of sufficient length to register simultaneously 90 with the upper ends of said chamber and one of the ports e , as shown by full lines in Fig. 2 and by dotted lines in Fig. 1. For 95 this purpose all of the ports e terminate at the flat top of the block B which forms the seat of said valve. A spring f^2 applied to the screw f between its head and the outer side of the valve serves to press the latter 100 constantly against its seat, insuring a tight joint.

While but two stops are illustrated in Fig. 2, it will be observed that in Fig. 1 sixteen ports e are shown, making provision 105 for that number of stops. An inner row of additional ports e^1 is preferably employed, these ports being fewer in number than

those of the outer row and arranged in radial alinement with some of them. Each of these additional ports is connected by a conduit d^1 with the motor of another stop, 5 so that whenever the radial port f' of the valve F is turned into register with two of such radially alined ports e , e^1 , the two corresponding stops are simultaneously brought into action, while when said radial 10 port is brought into register with any of the ports e having no companion port e^1 only the single corresponding stop is thrown on.

H indicates a block or case containing a 15 suction chamber h which is constantly connected by a passage h^1 with a suction bellows or other exhaust device, not shown in the drawings. Leading from the top of the exhaust chamber h to the upper surface of 20 the block H is a suction port i and adjacent to this port is a second port i^1 extending downwardly from the top of the block. The wind chamber E^1 is connected with the last-named port by a tube or conduit i^2 .

25 The top of the block H forms a valve seat to which is applied a valve J, preferably a slide-valve, provided in its underside with a longitudinal port or groove j of such length that when the valve is shifted to the 30 right hand extremity of its stroke, said port connects the two ports i , i^1 , placing the chamber E^1 in communication with the suction chamber h , while when the valve is shifted to the opposite extremity of its 35 stroke, it cuts off communication between the suction chamber h and the chamber E^1 and uncovers the port i^1 , opening the latter to the atmosphere, which under these conditions flushes the chamber E^1 through the 40 conduit i^2 , thus expanding the particular motor C which for the time being is in communication with the chamber E^1 and throwing off the corresponding stop.

The slide valve J may be guided by any 45 suitable means, the devices shown in the drawings consisting of pins k secured to the top of the block H and passing through longitudinal slots k^1 in the valve. This valve is reciprocated by a pair of motors or 50 motor pneumatics L, L^1 secured to opposite sides of the block H, the movable boards of these pneumatics closing in opposite directions and carrying arms l , l^1 , respectively, arranged to bear against opposite ends of 55 said slide valve. These valve operating pneumatics are controlled by pneumatic actions or valve mechanisms M, M^1 of any suitable construction which in turn are controlled by the ducts a^1 , a^2 of the tracker and 60 corresponding performances of the music sheet. In practice, the devices M, M^1 are built in the usual wind chest and form part of the ordinary pneumatic action. Those 65 shown in the drawings are of conventional form, each comprising the usual valve

chamber m , suction chamber m^1 , and valves m^2 , m^3 , controlling the suction and flushing ports n , n^1 , and actuated by the diaphragm o.

p , p^1 are the tubes or conduits leading 70 from the tracker ducts a^1 , a^2 to the chambers underneath the diaphragms o.

In the construction shown in the drawings, the valve F is intermittently rotated by a pawl q carried by the arm l of the left-hand motor pneumatic L, which shifts the slide valve J to the position in which one or more of the stops are thrown into action. This pawl engages the teeth at the edge of the rotary valve, these teeth being so spaced 80 that said valve is turned one step, or the distance between adjacent ports e thereof, for every stroke of the pawl.

The operation of the apparatus is as follows: As shown in the drawings, the slide 85 valve J is in its initial position in which the wind chamber E^1 is in communication with the atmosphere through the uncovered port i^1 and cut off from the suction chamber h . The stop-operating motors C are therefore 90 inflated and the stops are thrown off. When one of the "on" perforations of the music sheet registers with the corresponding tracker duct a^1 , the flushing valve m^3 is 95 closed and the suction valve m^2 opened, connecting the motor pneumatic L with the suction chamber m^1 and collapsing it. By this action, the slide valve J is shifted to the position shown by dotted lines in Fig. 1, connecting the chamber E^1 with the suction 100 chamber h . Simultaneously with this movement, the feed pawl q is moved forward and caused to turn the rotary valve F the distance of one tooth, thereby bringing the valve-port f^1 into register with one or more 105 of the ports e , e^1 , as the case may be, and connecting the corresponding motor pneumatic C with the chamber E^1 , which motor is thus collapsed and throws the stop "on".

The corresponding spring e is extended by 110 this movement. As soon as said music-sheet perforation passes the tracker duct a^1 , the motor pneumatic L is flushed and expanded in an obvious manner, withdrawing the feed pawl q to its initial position. The slide 115 valve J however remains undisturbed and the stop-motor C therefore remains collapsed, keeping the stop "on" until an "off" perforation of the music sheet registers with the tracker duct a^2 . When this occurs, the 120 motor L^1 is collapsed and pushes the slide valve J to its original position, as shown by full lines in Fig. 1, cutting off further communication between the chamber E^1 and the suction chamber h . Atmosphere is now 125 admitted to the chamber E^1 through the port i^1 and all the collapsed motor pneumatics C are inflated, shifting the stop-slides to the closed position shown in the drawings and throwing off all the stops. 130

This movement of the slides is effected partly by the reaction of the springs *c*. When the next "on" perforation of the music sheet passes over the tracker, the feed pawl *q* receives another impulse and turns the rotary valve *F* another step, and at the same time the slide valve *J* is again shifted to the "on" position, thus bringing a new stop or stops into action, and so on throughout the entire series of stop-operating devices controlled by the rotary valve.

Heretofore a pair of on and off tracker ducts and corresponding music-sheet perforations were required for each stop, rendering it impracticable to employ a large number of stops on account of unduly widening the music sheet. My improved apparatus, while permitting the use of a considerable number of stops does not require a separate pair of such ducts for each stop but only a single pair for controlling all of the stops, leaving the music sheet practically as narrow as an ordinary one and insuring proper tracking.

25 While the improvement is herein shown and described in connection with stops, the same could obviously be used for operating or controlling a plurality of other movable parts of the instrument.

30 I claim as my invention:

1. An apparatus for operating a plurality of stops, comprising a motor pneumatics for controlling the stops, a wind chamber, means for alternately exhausting and flushing said chamber, switching means for connecting one or more of said motor pneumatics with said wind chamber, and means for controlling said switching means.

40 2. An apparatus for operating a plurality of stops, comprising motor pneumatics for controlling the stops, a wind chamber, valve mechanism controlling the passage of the air to and from said chamber, switch mechanism for connecting one or more of said motor pneumatics with said wind chamber, a tracker having a pair of "on" and "off" ducts, and pneumatic actions coöperating with said tracker ducts and controlling said valve and switching mechanisms.

45 3. An apparatus for operating a plurality of stops comprising motor pneumatics for controlling the stops, a wind chamber, means for alternately exhausting and flushing said chamber, a rotary switch-valve for connecting one or more of said motor pneumatics with said wind chamber, and means for actuating said valve.

50 4. An apparatus for operating a plurality of stops comprising motor pneumatics for controlling the stops, a wind chamber, means for alternately exhausting and flushing said chamber, a rotary switch-valve for connecting one or more of said motor pneumatics with said wind chamber, and pneumatic means for actuating said valve.

5. An apparatus for operating a plurality of stops, comprising a case containing a wind chamber and a plurality of ports, a plurality of motor pneumatics for controlling the stops respectively connected with said ports, and a rotary valve having a port arranged to connect one or more of the first-named ports with said wind chamber.

6. An apparatus for operating a plurality of stops, comprising a case containing a wind chamber and a circular series of ports surrounding said chamber, a plurality of motor-pneumatics for controlling the stops respectively connected with said ports, and a rotary disk-valve having a radial port constantly connected with said wind chamber and arranged to traverse said circular series of ports.

7. An apparatus for operating a plurality of stops, comprising a case containing a wind chamber and a plurality of ports, a plurality of motor-pneumatics for controlling the stops respectively connected with said ports, a rotary valve having a port arranged to connect one or more of the first-named ports with said wind chamber, and ratchet mechanism for rotating said valve.

8. An apparatus for operating a plurality of stops, comprising a case containing a wind chamber and a plurality of ports, a plurality of motor-pneumatics for controlling the stops respectively connected with said ports, a rotary disk valve having ratchet teeth and a port arranged to connect one or more of the first-named ports with said wind-chamber, a feed pawl engaging the teeth of the valve, and a pneumatic for actuating said pawl.

9. An apparatus for operating a plurality of stops, comprising a tracker having a pair of "on" and "off" ducts, a corresponding pair of motor pneumatics, means coöperating with said ducts for controlling the passage of the air to and from said pneumatics, a case containing a suction chamber and a port adapted to communicate alternately with said chamber and the atmosphere, a valve controlling said port and operated by said pneumatics, a second case containing a wind chamber and a series of stop-controlling ports, said wind chamber being connected with the port of the first-named case, a valve constructed to connect one or more of said stop-controlling ports with said wind chamber and actuated by the motor-pneumatic corresponding to said "on" duct, and stop-controlling motors connected with the last-named ports.

10. An apparatus for operating a plurality of stops, comprising a tracker having a pair of "on" and "off" ducts, a corresponding pair of motor pneumatics, means coöperating with said ducts for controlling the passage of the air to and from said pneumatics, a case containing a suction cham-

- ber and a port adapted to communicate alternately with said chamber and the atmosphere, a valve controlling said port and operated by said pneumatics, a second case 5 containing a wind chamber and a series of stop-controlling ports, said wind chamber being connected with the port of the first-named case, a valve constructed to connect one or more of said stop-controlling ports 10 with said wind chamber, means controlled by the pneumatic corresponding to said "on" duct for actuating the last-named valve, and stop-controlling motors connected with the ports of the second-named case.
- 15 11. An apparatus for operating a plurality of stops, comprising a tracker having a pair of "on" and "off" ducts, a corresponding pair of motor pneumatics, means coöperating with said ducts for controlling 20 the passage of the air to and from said pneumatics, a case containing a suction
- chamber and a port adapted to communicate alternately with said chamber and the atmosphere, a slide valve controlling said port and reciprocated by said pneumatics, a second case containing a wind chamber and a circular series of stop-controlling ports, said wind chamber being connected with the port of the first-named case, a rotary ratchet disk having a port arranged to connect one 30 or more of said stop controlling ports with said wind chamber, a feed pawl engaging said disk and actuated by said "on" pneumatic, and stop-controlling motors connected with the last-named ports. 35

Witness my hand this 11th day of December, 1911.

ROBERT HOPE-JONES.
